CUTTER

Filed Sept. 23, 1927

UNITED STATES PATENT OFFICE

WINFIELD S. JONES, OF LONG BEACH, CALIFORNIA, ASSIGNOR, BY DIRECT AND MESNE ASSIGNMENTS, TO KAMMERER CORPORATION, OF SANTA FE SPRINGS, CALIFORNIA, A CORPORATION OF CALIFORNIA

CUTTER

Application filed September 23, 1927. Serial No. 221,489.

This invention contemplates an improvement upon my invention for cutter as described in United States Letters Patent granted me January 18, 1927, No. 1,614,840.

5 In particular the present invention contemplates a novel means and method whereby the cutter blades of said cutter are maintained in a definite position during lowering of my cutter within a well hole. In particular the cutter about to be described is known as an outside downwardly acting cutter in that the said cutter is adapted to surround the pipe to be cut and the cutters are adapted to be projected into engagement with the outer 10 side of the pipe for a cutting operation upon a downward movement of the said cutter.

An object of the present invention is to provide a novel and simple means for maintaining the cutter blades in a given position, 20 and which is positive and likewise fool-proof in its operation. In a device of this character, it is essential that some positive means be utilized for maintaining the cutter blades in a given position until it is desired to operate the cutter. Various yielding means such as springs have been utilized for this purpose, but are not always satisfactory due to various abrasive material within the well hole which tends to break such members and allow 25 the cutter blades to contact with different objects within the well hole, which often ruin the cutter blades. The present invention overcomes this defect by providing means for positively maintaining the cutter blades in 30 a certain position against movement at all times when the cutter is being lowered within the well hole and until it is desired to utilize said cutter.

In the drawing:

40 Fig. 1 is a vertical sectional elevation of the improved cutter as an entirety and utilizing the improved invention;

Fig. 2 is a fragmentary detail in vertical section of the cutter blades and the means 45 for operating the said cutter blades;

Fig. 3 is a transverse section on the line 3—3 of Fig. 2;

50 Fig. 4 is a sectional elevation of a modified form of means for holding the cutter blades in a given position;

Fig. 5 is a cross sectional view on the line 5—5 of Fig. 4;

Fig. 6 is an elevation of the means shown in Figs. 4 and 5;

Fig. 7 is a vertical elevation of a modified 55 form of the means for holding the cutter blade;

Fig. 8 is a cross sectional view on the line 8—8 of Fig. 7; and

Fig. 9 is a fragmentary cross sectional view 60 on an enlarged scale of a trip or latch element associated with the cutter.

Corresponding parts in all the figures are designated by the same reference characters.

Referring now with particularity to the drawing, the improved cutter as an entirety and as shown in Fig. 1, is designated by A. This cutter includes in combination the following elements: an annular cutter shell a, one end of which is secured to drive tubing b and the opposite end of which is secured to an annular latch barrel c. Within the cutter shell and likewise secured to the latch barrel is a friction carrier sleeve d, which sleeve d carries bowed springs e adapted to engage the periphery of drill stem pipe B. Also within the said cutter sleeve is a drive sleeve f, which is connected through the medium of a rotatable connector g with a stool cage h. Cutters j are hingedly connected to 75 the cutter sleeve and are received within slots of the cutter shell. The upper end of the drive sleeve f is bevelled as shown at 1 for engagement with the cutter blades. Included as between the drive sleeve and the 80 cutter shell is a coil spring 2. The stool cage h is adapted to carry stools 3, which stools are confined within slots of the stool cage. A latch k is carried by the latch barrel c and when in the position shown in Fig. 90 1 locks the friction carrier sleeve and cutter shell, through the medium of the latch barrel, together. The latch k is receivable within a slot 33 in the latch barrel c and said latch is held in latching position by a pin 34 passing therethrough and into the wall of the member c, said latch being formed with a shouldered portion 35, with a coil spring 36 wrapped about the pin 34 and having one end engaging the shoulder 35 and the other

95

100

end engaging with a wall bounding the slot 33. Said latch is formed with a notch 37 and a limiting pin 38 is carried by the member *c* to limit outward swinging of the latch, 5 said pin 38 being received in the notch 37 when the latch is urged outwardly by the spring 36 so as to release the member *c* from the member *d*. The latch is formed with a shouldered end 39 and the normal position 10 for said latch is that shown in Figure 9, the latch being held in such position, inwardly from the slot 33, by a small wire, or other frangible shear element 40, passed through an opening in said latch and having its 15 end or ends bearing against the inner face of the member *c*. The latch when in the position shown in Figure 9 is adapted to be received in a keeper notch or slot 41 of the member *d* and thus prevent the member *c* 20 from being rotated to disconnect it from the member *d*. As the drive tubing moves the cutter downwardly, the stools 3 will, due to movement of the friction carrier sleeve upwardly, engage the coupling *m* and in so 25 doing will permit the drive sleeve *f* to engage the cutter or cutter blades *j* and force the same inwardly for engagement with the drill stem pipe, as shown by the dotted lines for said cutter blade in Fig. 2.

30 It is essential, as has been stated in the objects, that the cutter blades be maintained within the slot or slots of the cutter shell during lowering operation of the cutter as an entirety within the well hole. This is accomplished through any one of the several means shown in Figs. 2 to 8 inclusive. The form of the invention shown in Figs. 2 and 3 is designated as C; the form shown in Figs. 4, 5 and 6 by D, and Figs. 7 and 8 40 by E. All of the said means operate on the same principle and comprise a positive and yet yieldable means for holding the cutter blade against movement until the drive sleeve engages the cutter to positively move the same into engagement with the drill stem pipe.

The form shown and designated by C includes a wire or the like, which is severable upon movement of the cutter blade. In this 50 connection the said member surrounds in part the cutter blade *j* as shown at 10 with ends of said member anchored in the cutter shell by being received within slots of the cutter shell as shown at 11 and 12. When 55 the drive sleeve *f* is moved to engage the cutter blade, the cutter blade will shear the said means and release the cutter. It is obvious that until such means is sheared that the cutter blade is maintained within the 60 slot of the cutter shell. The said means is readily replaceable as would be obvious.

The form of the invention designated as D comprises a shearable or frangible pin 20, passed through a bore 21 in the cutter shell *a*, 65 with a portion of said frangible pin received

within a recess or bore 22 of the cutter blade, the operation would be the same as before. This pin 20 may be slightly tapered so that the same may be readily removed from the bore 21 after the same has been sheared, if desired, and in this connection the recess 22 would likewise be slightly tapered for the same reason. Thus it is possible to keep moving the pin inwardly as lengths thereof are sheared and until the pin is entirely used up.

70 The form of the invention designated as E likewise includes a pin 30 passed through a bore 31 in the drive sleeve *f*. In this connection the cutter blade is provided on one face thereof with an inclined groove 32 and within which groove the said pin is in part received. Thus when the driving sleeve is moved upwardly the pin is sheared as it travels along said inclined groove.

75 The operation is as follows:

Assuming that the parts are in the position shown in Fig. 1, in which it will be noted that the cutter elements *j* are out of contact with the periphery of the drill stem *B*, the latch *k* is in the position of service or, in other words, in position to maintain the members *c*, *d* in working relation and in such relation that they do not unscrew from one another. The member *A* has been lowered by means of the drive tubing *b* and the lower end of said 80 member *A* may carry a wash-over shoe, not shown, which may be screwed into the lower end of the latch barrel *c*. The stools 3 are out of position of service and the spring member *e* is in engagement with the periphery of the drill stem *B*. When the latch *k* contacts with the ledge in a coupling *m*, joining two 85 lengths of the drill stem *B*, the means 40, will be sheared and the latch member *k* retracted by the spring 36 within the slot 33 of the member *c*. It may be necessary to 90 rotate the member *A* through the medium of the drive tubing *b* in order that it may reach a desired location within the well hole, and a further turning of the member *b*, will, when 95 the latch *k* has been retracted by the spring, 100 unscrew the member *d* from the member *c*, thus permitting the member *d* to be moved downwardly. This downward movement of the member *D* will be constrained by the 105 spring *e* being in frictional engagement with the periphery of the drill stem *B*, and the cutter shell *a* upon its continuous downward movement will cause the expansible member 2 to be compressed, thus permitting continued 110 movement of the parts to position where the stools 3 will have their legs in engagement with the ledge formed by the upper end of the coupling *m*; this being effected by the member *d* moving relative to the shell *a* and 115 forcing the stools 3 inwardly so that the leg members thereof engage with the ledge of the coupling. Furthermore, this downward movement of the shell *a* relative to the member *d* likewise effects a relative movement be- 120

125

tween the members *f* and *a* inasmuch as the members *h* and *f* are coupled by the rotatable connection *g*. The bevelled upper end *l* of the sleeve *f* will force the cutters *j* into engagement with the periphery of the stem *B* to cut the same.

70 It is obvious that various changes, modifications and variations may be made in practising the invention in departure from the particular showing of the drawing without departing from the true spirit thereof.

75 Having thus disclosed my invention, I claim and desire to secure by Letters Patent:

80 A cutter for oil well tubing and the like comprising a cutter shell, a cutter blade carried thereby, means for moving said cutter blade into tubing engagement, and means secured to the cutter shell and engaging the cutter blade for positively maintaining said cutter blade in a given position relative to the cutter sleeve until said cutter blade is actuated by said first named means, said second named means comprising a frangible U-shaped member embracing the cutter, the 85 out-turned ends of the frangible member being anchored in slots in the outer face of the shell.

90 In testimony whereof, I have signed my name to this specification.
